Attorney

UNITED STATES PATENT OFFICE.

JOSEPH LINDBURG, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed February 12, 1924. Serial No. 692,282.

This invention relates to means for retaining a typewriting machine on a desk. Heretofore, there has been a direct connection between the machine and the baseboard, thus providing a conductor for vibrations, and tending to augment the sound.

It is desirable to minimize or eliminate the conduction of sound-vibrations to the outside support. An object of the present invention is to provide a retaining device for such purpose. There are used a sound-dampening box and also spaced sockets in a baseboard for the rubber feet of the box, which encases the typewriting machine.

Fastening elements prevent the typewriting machine from being lifted, but do not contact with any part of the machine, and hence do not propagate sound.

Each of said fastening elements may be in the form of an upwardly-extending, pivoted clamp pressed by a spring over the machine-frame, and swinging to allow the machine with its casing to be lifted free from the baseboard.

The clamps are arranged to be clear of the machine-frame, so that nothing but a sound-absorbing material is interposed between the typewriter and its baseboard; but when the support is swung to an inclined position to lower the machine into the back part of the desk, the retaining device confines the machine to such support. The fastening element has a foot which is pressed against a soft pad, to keep the fastening element from swinging into contact with the typewriter-frame.

Other features and advantages will herein-after appear.

In the accompanying drawings,

Figure 1 is a view in front elevation of a fragmentary portion of a typewriting machine fitted in a sound-absorbing casing and mounted on a baseboard, showing the retaining clamps for holding the machine against accidental displacement from its support, but normally not in contact with the machine, to avoid transmission of sound-producing vibration to the support.

Figure 2 is a fragmentary side view of that shown in Figure 1.

Referring to the drawings, 10 denotes a hinged desk, top, baseboard or other support for a typewriting machine 11, which is encased in a sound-dampening box or casing 12. The sound-dampening box 12 may be

like that disclosed in the application of Cornelius B. Corcoran, No. 604,468, filed December 2, 1922 (now Patent No. 1,509,828, dated September 30, 1924). Cups or sockets 13 may be fastened to the base 10 by screws 14, and said sockets 13 may be spaced to receive the rubber feet 12^a of the casing 12 to prevent sliding thereof and to hold the machine 11 against displacement, except in an upward direction, from the base 10.

In order to prevent the machine 11 and casing 12 from leaving their support 10 when the latter is tilted, suitable fastening devices mounted on base 10 are provided, which may consist of upwardly-projecting catches 15 having their engaging ends or hooks 16 extending inwardly from the outer edge of the baseboard 10 over the front-extending machine-frame sides 11^a, as shown in Figures 1 and 2. The catches 15 at their lower ends may have lateral offsets which are pivoted between ears 17 of fastening members 18, which are firmly secured to base 10, as by screws 19. A coil compression spring 20 may be arranged between the offset portions of catches 15 and members 18, to urge the catches 15 inwardly until catches 15 strike stops 21 on members 18.

As shown in Figure 2, the catches 15 do not anywhere contact with the machine-frame sides 11^a when the machine 11 is in normal typewriting position. Thus the possibility of conducting sound-producing vibrations outside the casing 12 to the supporting base 10 is eliminated. However, when the baseboard 10 is swung to an inclined position, the hooks 16 of the catches 15 engage the frame sides 11^a and prevent the machine 11 and its casing 12 from leaving the base. By simply swinging catches 15 outwardly, the machine 11 and its casing 12 may be removed by lifting same free from the base 10.

When the machine occupies its typing position on the baseboard, as shown in the drawings, each hook occupies such a position with relation to the machine that the hook and machine do not contact with each other, this want of contact being secured partly by the form of the lower or pivoted end of the hook and partly by placing the upper or hooked end of the hook at such an altitude above the machine as to keep them out of engagement; this construction being the means referred to in the subjoined claim.

Variations may be resorted to within the scope of the invention, and portions of the improvements may be used without others.

Having thus described my invention, I claim:

The combination of a typewriting machine, a sound-deadening box enclosing the machine, feet on the box, a tilting support on which the box and machine are mounted, 10 sockets on the support in which the feet on

the box are placed, catches mounted on the support arranged automatically to engage the machine when the support is tilted, and prevent the machine and box from falling off of the support in its tilted position, and means for preventing the catches from engaging the machine and box with said support in a level position during the typewriting operation.

JOSEPH LINDBURG.
